SEPARABLE FASTENER SLIDER

Bernard A. Kotowski, Meadville, Pa., assignor to
Hookless Fastener Company, a corporation of
Pennsylvania

Application May 26, 1934, Serial No. 727,757

8 Claims. (Cl. 24—205)

This invention relates to slide fasteners and more particularly to locking sliders for slide fasteners. Various types of locking sliders have been proposed and many of them have been actually used for the purpose of preventing the slider slipping along the rows of fastener members and allowing the fastener to open up unintentionally.

The present invention is an improvement on the locking slider construction shown in the Whitney Patent No. 1,858,351, May 17, 1932, which discloses the idea of slitting away a portion of the top wing and providing a cam member for flexing such slitted portion into contact with the fastener members. According to the present invention, no attempt is made to flex the outer flanged parts of the slider but instead this invention provides a central shoe which is integrally but flexibly connected to the remaining portions of the wing. It will be appreciated that the amount of metal available in a small slider is quite small and it is therefore convenient to attach the pull to two loops and form the locking shoe from metal between such loops. The pull member is attached to the loops and carries a cam between the loops for acting on the locking shoe.

In the accompanying drawing, I have shown for purposes of illustration two embodiments which my invention may assume in practice. In the drawing:

Fig. 1 is a plan view of a slide fastener embodying my invention;

Fig. 2 is a longitudinal section on line 2—2 of Fig. 1;

Fig. 3 is a cross-section on line 3—3 of Fig. 1;

Fig. 4 is a perspective view of the slider detached;

Fig. 5 is a plan view of a modified form of slider; and

Fig. 6 is a longitudinal central section through Fig. 5.

The slide fastener comprises rows of fastener elements 7 arranged in uniformly spaced relation on the edges of a pair of tapes 8. The form of fastener elements and tape constitutes no part of the present invention, and it will be understood that they might be of any well-known form. It is sufficient to say here that they are formed with appropriate interlocking parts which can be quickly engaged and disengaged by a slider. The slider 9 has a Y-shaped channel through which the fastener members are guided during engagement and disengagement.

Referring to Fig. 4, the slider comprises top

and bottom sheet metal wings 10, 11, respectively, having side flanges 12 and integrally connected at one end by a relatively thick neck 13. A pair of loops 14 are struck up from the metal of the top wing on opposite sides of the central portion and a pull tab 15 is pivotally mounted in said loops. The central portion of the slider is cut out to provide a locking shoe in the form of a square block 16 which is integrally connected to the slider by a narrow section of metal constituting a flexible arm 17. Preferably the connection is with the forward or narrow end of the slider since, in this manner, the arm can be made longer and it will not extend into the thickened neck portion 13.

In the modified construction shown in Figs. 5 and 6, the locking shoe 18 is similar to the locking shoe 16 but is connected at its back end to the slider wing which necessitates the loops 14 being located farther from the rear end of the slider. In order to make the connection more flexible in this instance, the metal is thinned or necked down as shown at 19 and in this case, the connecting arm need not be any narrower than the shoe itself. The working of the metal in thinning the neck at 19 increases the resilience of the connection.

The pull tab 15 carries cams 20 disposed on opposite sides and in the same transverse line as the pivot. When swung down against the slider in either direction one or the other of these cams will bear against the locking shoe and depress it into engagement with the fastener elements, thus causing the slider to be frictionally held against movement on the fastener members. The resiliency of the arm 17 will lift the locking shoe away from the fastener elements as soon as the pull tab is lifted.

While I have shown and described in this application two embodiments which my invention may assume in practice, it will be understood that these embodiments are merely for the purposes of illustration and description and that various other forms may be devised within the scope of my invention as defined in the appended claims.

What I claim as my invention is:

1. In a slide fastener having rows of fastener elements, a slider movable along said elements to engage or disengage them, said slider comprising parallel wings having channels for guiding interlocking members, a connection between said wings, one wing having an opening, a relatively wide shoe movable through said opening into engagement with the fastener elements, said

shoe being integrally connected to the wing by a relatively narrow resilient arm, and a cam member attached to the slider for depressing said shoe into engagement with the fastener elements 5 to lock the slider.

2. In a slide fastener having rows of fastener elements, a slider movable along said elements to engage and disengage them, said slider comprising sheet metal wings, the top wing having 10 a central portion cut out to provide a relatively wide locking shoe integrally connected by a relatively narrow arm with the said top wing, a pull tab pivotally secured to the top wing adjacent said shoe and having a cam adapted to depress 15 said shoe into engagement with the fastener elements for locking the slider.

3. In a slide fastener having rows of fastener elements, a slider movable along said elements to engage and disengage them, said slider comprising parallel wings having channels for guiding interlocking members, a neck integral with 20 said wings for connecting them at one end, said wings having flanges along their side edges, a portion of the metal of one wing being cut away 25 from said wing except for a relatively wide locking shoe and narrow flexible connection, and a pull tab pivoted to said top wing adjacent said shoe and having a cam for depressing said shoe 30 into locking engagement with the fastener elements, said locking shoe being movable relative to the flanges of the slider.

4. In a slide fastener having rows of fastener elements, a slider movable along said elements to engage and disengage them, said slider comprising parallel wings integrally connected at 35 one end, a relatively wide locking shoe cut out from the central portion of one of said wings and connected to such wing by a relatively narrow resilient arm, a pair of pull attaching loops 40 at opposite sides of said arm, a pull tab pivotally connected to said loops having a cam arranged between said loops for depressing said locking shoe into engagement with the fastener elements.

45 5. A slider for a slide fastener having rows of fastener elements comprising means movable along said elements to engage and disengage them, said means including parallel wings having channels for guiding interlocking members,

a connection between said wings, one wing having an opening, a locking shoe of relatively large cross-section movable through said opening into engagement with the fastener elements, said shoe being integrally connected to the wing by 5 a resilient connection of relatively small cross-section, and a cam attached to the slider for holding the shoe in engagement with the fastener elements to lock the slider.

6. In a slide fastener having rows of fastener 10 elements, a slider movable along said elements to engage or disengage them, said slider comprising parallel wings having channels for guiding interlocking members, a connection between said wings, one wing having an opening, a shoe 15 movable through said opening into engagement with the fastener elements, said shoe being integrally connected to the wing by a resilient arm, said arm being thinner than said shoe, and a cam member attached to the slider for depressing said 20 shoe into engagement with the fastener elements to lock the slider.

7. In a slide fastener having rows of fastener elements, a slider movable along said elements to engage or disengage them, said slider comprising parallel wings having channels for guiding interlocking members, a connection between 25 said wings, one wing having an opening, a shoe movable through said opening into engagement with the fastener elements, said shoe being integrally connected to the wing by a resilient arm of compressed wing material, and a cam member attached to the slider for depressing said 30 shoe into engagement with the fastener elements to lock the slider.

8. In a slide fastener having rows of fastener elements, a slider movable along said elements to engage or disengage them, said slider comprising parallel wings having channels for guiding interlocking members, a connection between 40 said wings, one wing having an opening, a shoe movable through said opening into engagement with the fastener elements, said shoe being integrally connected to the wing by a resilient arm, the material of the arm being worked to increase its resiliency, and a cam member attached to the slider for depressing said shoe into engagement with the fastener elements to lock the slider.
